Primary Examiner — Ramzi Almatrahi(74) *Attorney, Agent, or Firm* — Berg Hill Greenleaf Ruscitti, LLP(57) **CLAIM**

The ornamental design for a camera base, as shown and described.

DESCRIPTION

FIG. 1 is a top perspective view of a camera base;
 FIG. 2 is a bottom perspective view thereof;
 FIG. 3 is a front elevation view thereof;
 FIG. 4 is a rear elevation view thereof;
 FIG. 5 is a left-side elevation view thereof;
 FIG. 6 is a right-side elevation view thereof;
 FIG. 7 is a top plan view thereof; and,
 FIG. 8 is a bottom plan view thereof.

The broken lines depict portions of the camera base in which the design is embodied that form no part of the claimed design.
